(57) **CLAIM**

The ornamental design for a faucet set, as shown and described.

DESCRIPTION

FIG. 1 is a perspective view of a faucet set showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a perspective view of a second embodiment thereof, with the broken-line disclosure of faucet set base being for illustrative purposes only and forming no part of the claimed design; and,

FIG. 8 is a perspective view of a third embodiment thereof, with the broken-line disclosure of faucet set base being for illustrative purposes only and forming no part of the claimed design.
